Primary Examiner — Michael A Maharajh(74) *Attorney, Agent, or Firm* — Wolf, Greenfield & Sacks, P.C.(57) **CLAIM**

The ornamental design for an electrical stimulation device, as shown and described.

DESCRIPTION

FIG. 1 is a top perspective view of an electrical stimulation device, in accordance with the present design;
FIG. 2 is a front elevational view thereof;
FIG. 3 is a left side elevational view thereof;
FIG. 4 is a rear elevational view thereof;
FIG. 5 is a right side elevational view thereof;
FIG. 6 is a top plan view shown at a larger scale thereof; and,
FIG. 7 is a bottom plan view shown at a larger scale thereof.
